UNITED STATES PATENT OFFICE.

GEORGE W. BLAIR, OF PITTSBURG, PENNSYLVANIA.

DESIGN FOR A BOX.

SPECIFICATION forming part of Design No. 30,563, dated April 18, 1899.

Application filed December 8, 1898. Serial No. 698,680. Term of patent 7 years.

To all whom it may concern:

Be it known that I, GEORGE W. BLAIR, a citizen of the United States, residing at Pittsburgh, in the county of Allegheny and State of Pennsylvania, have invented and produced a certain new and original Design for Boxes, of which design the following is a specification.

In the accompanying drawing, forming a part of this specification, is shown a perspective view of my design for a box.

As shown in the drawing, the leading feature of the design consists of a rectangular top or body portion 1, having its upper and lower peripheral edges beveled, as at 2. The cover or body portion has a recessed or de-

pressed portion 3 in its upper side. The sides 4 and the raised portions 5, surrounding the recess 3, have V-shaped grooves 6, extending transversely across them. This cover or body portion rests upon a base or bottom portion 7. 20

I claim herein as my invention—

The design for a box as herein shown and described.

In testimony whereof I have hereunto set my hand.

GEORGE W. BLAIR.
